SELF-ADJUSTING SOCKET WRENCH
Fred D. Svenson, R.F.D. 1, Box 175, Sanbornton, N.H.
Filed June 30, 1965, Ser. No. 468,309
7 Claims. (Cl. 81—185)

The present invention relates to a tool of the socket type that is self-adjusting to fit any one of a series of fastener parts of different sizes but of the same equilateral shape.

Where, for example, a workman must tighten or release a plurality of nuts of the same shape but of different sizes, a single tool that is self-adjusting to fit any one of them would eliminate the inconveniences and disadvantages that attend the use of a number of separate tools.

In Letters Patent No. 2,875,660, there is shown such a tool, the tool comprising a plurality of slidably nested sockets of the same cross sectional shape but with each dimensioned to fit a particular one of a series of differently sized but similarly shaped fastener parts. The sockets have closed ends and the tool includes a stem to which the closed end of the largest socket is anchored and which slidably extends through the closed ends of the other sockets to slidably support them. The stem is provided with a plurality of seats, one for each socket and engageable by the end wall to limit the movement of that socket towards the free end of the fixed or anchored socket. The tool also includes a plurality of compression springs yieldably maintaining each slidable socket against its seat and the seats are so spaced and the socket length so selected that, when the sockets are seated, their free ends are substantially co-planar.

In use, such a tool is placed against a nut or a bolt head and the sockets that are undersized are pushed inwardly with the correctly sized socket fitting thereon. While this self-adjusting ability avoids the use of a plurality of tools or of a manually adjustable tool, one feature limits acceptance and that feature is that the springs serving to seat the sockets are operative to expel a fastener part that would otherwise be retained within the tool and that must usually be retrieved.

The general objective of the present invention is to provide tools of the type under discussion in which any socket may be held in its unseated position against the action of the compression spring that would otherwise seat it, when removed from the work, and expel a socketed fastener part.

In accordance with the invention, this objective is attained by providing the tool with a holding member to which the largest socket is anchored and which axially receives and rotatably supports the stem for rotation between a position in which the sockets slidably mounted thereon are free to be seated by their springs and a position holding them unseated against the seating action thereof. This objective is attained by providing the stem and the closed ends of the slidable sockets with portions that, when any socket has been unseated, are brought into holding engagement by such turning of the stem.

In the accompanying drawings, there are shown illustrative embodiments of the invention from which this and other of its objectives, novel features, and advantages will be readily apparent.

In the drawings:

FIGURE 1 is a partly sectioned side elevation of a tool in accordance with one embodiment of the invention.

FIGURE 2 is a like view of the stem and the stem-holding member.

FIGURE 3 is a longitudinal, fragmentary section, on an increased scale, of the stem, stem-holding member, and the sockets, the sockets being in their seated position.

FIGURE 4 is a section taken approximately along the indicated lines 4—4 of FIGURE 3,

2

FIGURE 5 is a view similar to FIGURE 3 but with the tool fitted to a bolt head and certain of the sockets unseated,

FIGURE 6 is a side elevation of a stem in accordance with another embodiment of the invention,

FIGURE 7 is a section taken approximately along the indicated lines 7—7 of FIGURE 6,

FIGURE 8 is a fragmentary, longitudinally sectioned view of a tool showing the sockets, the stem, and the stem-holding member, the sockets being in their seated position,

FIGURE 9 is a section taken approximately along the indicated lines 9—9 of FIGURE 8,

FIGURE 10 is a view similar to FIGURE 8 but with the tool fitted to a bolt head and with certain sockets being unseated and the stem turned into a position holding them unseated, and

FIGURE 11 is a section taken approximately along the indicated lines 11—11 of FIGURE 10.

In the embodiment of the invention illustrated by FIGURES 1—5, there are shown a set of slidably nested, closed-end sockets 20, 21, 22, 23, and 24 of hexagonal section and with their lengths increasing substantially as their cross sectional area increases. Each socket has an axial hole in its end wall, each end wall and its hole being distinguished by the suffix additions "A" and "B," respectively, to the reference numeral appropriate for that socket. The holes in the sockets 21, 22, 23, and 24 are notched in the manner of the hole 24B as shown in FIGURE 4.

The outermost socket 20 has its end wall 20A anchored as at 25 to one end of a tubular holding member 26 having a handle 27 fixed on its other end. The handle 27 is provided with an axial bore 28 intersected by a transverse slot 29.

A stem 30 is rotatably supported by the holding member 26 and extends freely into the bore 28 and has a pin 31 transversely threaded therein, the pin 31 extending outwardly through the slot 29 to enable the stem 30 to be manually turned within the limits determined by the length 35 of the slot 29. The stem 30 has a series of axially spaced, annular grooves 32, see FIGURE 2, each groove 32 receiving and holding a seat 33, the seats 33 being shown as conventional C-rings. The stem 30 extends through the holes in the closed ends of the sockets 21, 22, 23, and 24 in slidable support thereof and each seat 33 is engageable by the closed end of a respective one of the slideable sockets to limit the extent to which that socket may be slid towards the free end of the fixed, outermost socket 20. The lengths of the sockets 21, 22, 23, and 24 are such that, when seated, their free open ends are all substantially in the same plane.

The grooves 32 are shown as equally spaced from each other. There is, accordingly, a chamber 34 between each socket and the next smaller socket. Compression springs 35 are provided one in each chamber 34, yieldably to urge each slideable socket against its seat, each compression spring 35 engaging the end wall of a particular slideable socket and being backed by the seat 33 for the next larger socket.

In FIGURE 5, there is shown a bolt 36 interconnecting the members 37 and 38 and having a hexagonal head 39 and having a similarly shaped but somewhat smaller nut 40 threaded thereon. The socket 22 is dimensioned to fit the bolt head 36 while the socket 23 is dimensioned to fit the nut 40. In use, the tool is placed with the open socket ends against the bolt head 39. Either then or as the tool is turned, any socket that is undersized yields to admit the bolt head 39 into the appropriately sized socket, in this case, the socket 22, enabling the bolt to be turned and freed. Assuming that the nut 40 is to be similarly engaged, the tool would be used in the same manner. The nut 40, when detached, would

70

be within the socket 23 but, when the tool was moved away from the work, the nut would be expelled by the action of any spring backing any unseated socket.

For that reason, the stem 30 is provided with a screw thread portion 41 in each chamber 34. Each screw thread portion 41 is of an arcuate extent such that, when the stem-turning pin 31 is in position illustrated by FIGURES 1 and 3, it will pass freely through the notch of the hole in the end wall of each slideable socket. When, however, the tool has been applied to a fastener part, any socket that has been unseated then has its notch straddling the appropriate thread portion 41. If the stem 30 is now turned, 60° for example, to the other limit of the slot, the end wall of any unseated socket is engaged by a thread portion 41 thereby to hold that socket against the seating action of the associated spring until the stem 30 has been turned in the opposite direction to the appropriate extent. The turning of the stem 30 to hold any unseated socket has no effect on any seated socket as the thread portion 41 for holding the sockets 21, 22, and 23 terminates above the closed ends thereof. It will be noted that the thread portion 41 for holding the socket 24 has a key-like extension 41A extending downwardly into the notch of the hole 24B into engagement with the leading edge thereof thus to prevent the stem 31 from being turned unless the socket 24 is unseated.

In the embodiment of the invention illustrated by FIGURES 6-11, there is a set of slideably nested, closed end sockets 50, 51, 52, 53, and 54 which may be, as shown, identical to the sockets 20, 21, 22, 23, and 24 of the embodiment of the invention illustrated by FIGURES 1-5. Each of these has an axial hole in its end wall and the end walls and their holes being distinguished by the suffix additions "A" and "B" respectively, to the appropriate socket-identifying reference numeral.

The socket 50 has a tubular holding member 55 protruding from its end wall 50A with its end anchored in a handle 56 having an axial bore 57 intersected by a transverse slot 58 beyond the attached end of the holding member 55. A stem 59, shown as of flat stock but having its upper end within a cylindrical member 59A rotatably fitted within the bore 57, has a transverse pin 60 protruding outwardly through the slot 58 for manual engagement thereby to enable the stem 59 to be turned within the limits of the slots, say, through an arc of 60°.

The stem 59 extends axially of the socket 50 and has a series of axially spaced seats 61 and these may be C-rings caught in transversely aligned notches 62 in the edges of the stem 59, see FIGURE 6. Along one stem edge there is a series of outwardly and downwardly inclined shoulders 63, the shoulders for the sockets 51, 52, and 53 terminating close to but above the next lower seat 61 while the shoulder 63 for the socket 54 is shown as having an extension 63A. The holes in the end walls of the sockets 51, 52, 53, and 54 are shown as in the form of radial slots dimensioned to receive the shoulders 63 so that those sockets may be slideably supported by the stem 59 for movement into and out of engagement with their seats 61, see FIGURES 9 and 11. The lengths of the sockets 51, 52, 53, and 54 are such that, when seated, their free ends are all substantially in the same plane and chambers 64 of approximately the same axial extent are provided. Compression springs 65 are provided, one for each of the slideable sockets. Each spring 65 engages the closed end of a slideable socket and is backed by the seat 61 for the next larger socket.

The tool detailed in FIGURES 6-11 is used in the same manner as the tool illustrated by FIGURES 1-5. As will be apparent from FIGURE 10, when the tool is applied to a fastener part such as the bolt head 39 with the stem 59 positioned as illustrated by FIGURE 8, undersized sockets are forced inwardly against the action of their springs 65. By shifting the pin 60 to the other end of its slot 58, the stem 59 is turned to bring a

shoulder 63 under any unseated socket thereby to hold it against the action of the springs 65, see FIGURES 9 and 11. It has been noted that the shoulder 63 for the socket 54 has an extension 63A. The purpose of the extension 63A is to engage the edge of the slot 54B to prevent the stem 59 from being turned until the socket 54 has been unseated.

It will thus be apparent that tools in accordance with the invention are well adapted to meet all requirements of use since the ejecting action of the socket-seating springs may be prevented by the user.

I claim:

1. A tool for use in tightening and releasing any one of a series of fastener parts of the same equilateral shape 15 but of different sizes, said tool comprising a set of closed end sockets of said equilateral shape slideably nested one within the other, each socket being for a particular one of said different sizes and being substantially longer than any socket slideable within it, a tool holding member 20 to which the closed end of the outermost socket is anchored, a stem rotatable in said member and extending through the closed ends of the other sockets in slideable support thereof, a plurality of seats spaced lengthwise of said stem, one for each socket and engageable 25 by the end wall thereof to limit its movement towards the free end of said anchored socket, compression springs, one for each socket for yieldably maintaining each socket against its seat, each spring engaging the closed end of that socket and backed by the seat of the next larger 30 socket, the difference in length of said sockets being such that the free ends of said slideable sockets, when seated, are substantially in the plane of the free end of the anchored socket, and said stem and each of said slideable sockets including portions interengaging to hold 35 said socket, when unseated, against the seating action of its spring, when said stem has been turned relative to said holding member to a predetermined extent.

2. A tool for use in tightening and releasing any one of a series of fastener parts of the same equilateral shape 40 but of different sizes, said tool comprising a set of closed end sockets of said equilateral shape slideably nested one within the other, each socket being for a particular one of said different sizes and being substantially longer than any socket slideable within it, a tool holding member to 45 which the closed end of the outermost socket is anchored, a stem rotatable in said member and extending through the closed ends of the other sockets in slideable support thereof, a plurality of seats spaced lengthwise of said stem, one for each socket and engageable by the end wall thereof to limit its movement towards the free end of said anchored socket, compression springs, one for each 50 socket for yieldably maintaining each socket against its seat, each spring engaging the closed end of that socket and backed by the seat of the next larger socket, the difference in length of said sockets being such that the free 55 ends of said slideable sockets, when seated, are substantially in the plane of the free end of the anchored socket, said stem and each of said slideable sockets including portions interengaging to hold said socket, when unseated, against the seating action of its spring, when said stem 60 has been turned relative to said holding member to a predetermined extent, and means locking said stem to the smallest socket against being turned when said lowest socket is seated.

3. A tool for use in tightening and releasing any one of a series of fastener parts of the same equilateral shape 65 but of different sizes, said tool comprising a set of closed end sockets of said equilateral shape slideably nested one within the other, each socket being for a particular one of said different sizes, being substantially longer than any socket slideable within it, and having a hole through its closed end, a tool holding member to which the closed end of the outermost socket is anchored, a stem rotatable in said member and extending through the holes in the socket end walls of the other sockets in slideable support 70 thereof, means to turn said stem from a predetermined

position, a plurality of seats spaced lengthwise of said stem, one for each socket and engageable by the end wall thereof to limit its movement towards the free end of said anchored socket, compression springs, one for each socket for yieldably maintaining each socket against its seat, each spring engaging the closed end of that socket and backed by the seat of the next larger socket, the difference in length of said sockets being such that the free ends of said slideable sockets, when seated, are substantially in the plane of the free end of the anchored socket, said stem having outwardly disposed portions, one for each slideable socket and spaced above the closed end thereof when that socket is seated, the holes in the closed ends of the slideable sockets slidably receiving said stem portion when said stem is in said predetermined position and providing a shoulder portion, and each of said stem portions being inclined to engage with and support the shoulder of the subjacent socket when unseated and when said stem has been turned relative to said holding member from said predetermined position.

4. A tool for use in tightening and releasing any one of a series of fastener parts of the same equilateral shape but of different sizes, said tool comprising a set of closed end sockets of said equilateral shape slidably nested one within the other, each socket being for a particular one of said different sizes, being substantially longer than any socket slideable within it, and having a hole through its closed end, a tool holding member to which the closed end of the outermost socket is anchored, a stem rotatable in said member and extending through the holes in the socket end walls of the other sockets in slideable support thereof, means to turn said stem from a predetermined position, a plurality of seats spaced lengthwise of said stem, one for each socket and engageable by the end wall thereof to limit its movement towards the free end of said anchored socket, compression springs, one for each socket for yieldably maintaining each socket against its

seat, each spring engaging the closed end of that socket and backed by the seat of the next larger socket, the difference in length of said sockets being such that the free ends of said slideable sockets, when seated, are substantially in the plane of the free end of the anchored socket, said stem having outwardly disposed portions, one for each slideable socket and spaced above the closed end thereof when that socket is seated, the holes in the closed ends of the slideable sockets slidably receiving said stem portion when said stem is in said predetermined position and providing a shoulder portion, and each of said stem portions being inclined to engage with and support the shoulder of the subjacent socket when unseated and when said stem has been turned relative to said holding member from said predetermined position, and the stem portion for the smallest socket including an extension extending as a key through the hole in said smallest socket, when seated.

5. The tool of claim 3 in which each stem portion is disposed as a thread.

6. The tool of claim 3 in which each stem portion is outwardly and downwardly inclined.

7. The tool of claim 3 in which the stem is of flat stock and each stem portion is a shoulder at one edge thereof and is outwardly and downwardly inclined.
